UNITED STATES PATENT OFFICE.

CHAUNCEY L. C. MAGEE, OF CHICAGO, ILLINOIS.

FIRE ARCH.

Application filed September 5, 1922. Serial No. 586,332.

To all whom it may concern:

Be it known that I, CHAUNCEY L. C. MAGEE, a citizen of the United States, and resident of Chicago, Cook County, Illinois, have invented a certain new and useful Improvement in Fire Arches, of which the following is a specification.

This invention relates to tile construction for furnace arches or for other purposes, a furnace arch being one embodiment of the invention, so far as the more specific aspects of the invention are concerned, but in its broader aspects the invention may be used for other purposes.

Generally stated, the object of the invention is to provide a novel and improved form and construction of tile for heat resisting or heat insulating purposes, but adapted more particularly to use in furnaces where the heat is intense, and for other similar purposes.

It is also an object to provide certain details and features of construction tending to increase the general efficiency and desirability of tile construction of this particular character.

To these and other useful ends the invention consists in matters hereinafter set forth and claimed and shown in the accompanying drawings in which—

Figure 1 is a perspective of a tile embodying the principles of the invention.

Figure 2 is a cross section of the furnace showing a fire arch embodying the principles of the invention.

Figure 3 is a detail section on line 3—3 in Figure 2.

Figure 4 is a sectional view showing another form of fire arch embodying the invention.

As thus illustrated, and referring to Figure 1, the improved tile may be of any suitable form or design, but preferably comprises side wall 1 and 2, the walls 1 being higher than the walls 2 and having holes 3 for the supporting means hereinafter described. The hollow tile thus provided has a bottom wall 4, and the interior of the tile may be divided into compartments by the partitions 5, so that the tile is of a cellular character, the one shown having four rectangular cells or compartments which are closed at their lower ends and open at their top ends. In practice, the tile thus formed may

be made of any suitable material, but for some purposes it is preferably constructed of refractory material having a vitreous surface.

As shown in Figure 2, the tiles are supported by rods 6 in position to form a flat fire arch between the furnace walls 7, the furnace being of any suitable form or construction.

Cells or compartments of the tiles are preferably filled with soft fire clay 8, or any other light refractory and heat insulating material. Asbestos or other heat insulating material 9 may be placed on top of the tiles to seal them, and to prevent transmission of the heat in an upward direction.

The rods 6 are supported in any suitable manner, as by the steel or iron beams 10 suitably supported by the structure of the furnace. The filling 8 of each tile contributes nothing to the strength of the fire arch structure, and is merely a load thereon,

but serves to increase the heat insulating qualities of the fire arch and of the tiles to prevent upward transmission of the heat through the fire arch structure. In this way,

therefore, comparatively high grade material can be used in the construction and the manufacture of the tiles, such as the one shown in Figure 1, inasmuch as each tile comprises practically only a minimum of

such material, thus permitting the use of comparatively expensive material without increasing the cost of the tiles over and above those which are commonly made solid and of somewhat cheaper material. The fillings 8 are of very cheap and inexpensive material, of course, inasmuch as this material

does not sustain any structural strains, and is not required to contribute any strength to the structure, and serves merely as heat insulation to make the fire arch heat resist-

ing and prevent the transmission of the heat in an upward direction through the arch.

In Figure 4, the tiles are constructed in a manner similar to that previously described, but in this case each tile is tapered downward or somewhat wedge-shaped in form, inasmuch as the arch is curved and the tiles are self-supporting so to speak, and do not have the rod supports 6 previously

described. Thus, in this case, each tile 11 is made hollow and formed from high grade heat resisting material having a vitreous surface, if desired, and is provided with fillings

similar to the material 8 previously described and the top of each tile is sealed in any suitable manner, as by using plastic asbestos or fire clay or any other similar material which 5 will serve the purpose.

It is obvious, therefore, that the tiles thus constructed and formed can be used for various purposes, wherever heat insulation is required, the thin hard walls of the tiles 10 supplying the strength necessary for structural strains, with a minimum of such material, and the cheap and light fillings for each tile forming sufficient insulation to reduce the heat transmission to the point desired. While there is some material in the structure, such as the fillings 8, which does not contribute to the strength of the structure, it is at the same time obvious that by 15 using thin walls for the tiles high grade and very strong material can be employed which 20 will render the structure sufficiently strong as a whole, perhaps even stronger than would be obtained by using comparatively low grade solid material, and at the same 25 time by this method the structure is rendered lighter and even more heat resisting and less capable of transmission of the heat than would be the case with solid tiles made of certain other materials. In fact, the only 30 heat transmitted upward through the fire arch will be the small amount which is transmitted by the thin side walls of the tiles, inasmuch as the fillings 8 may be of absolutely non-heat conducting material, and 35 thus the heat is kept entirely below the arch and very little heat transmission will occur upward through the fire arch to the space immediately above. The fillings 8 may, for 40 example, be composed of fine ground fire clay, or other similar material. The material for the walls of the tile may be of superrefractory material of any suitable nature, and the links and pins 12 and 13 which 45 removably support the tiles on the rods 6 may be of hard iron or other suitable material. With this arrangement, the tiles are easily removed when broken or impaired by use, and repairs and substitutions are very easily made, it will be seen, without 50 the necessity of disturbing the entire arch. But the invention may be embodied, as shown and described, in an arch of the kind shown in Figure 4, or in other ways or in other structures, without departing from the spirit 55 of the invention.

The fire arch shown and described serves, therefore, to reduce or minimize the escape of heat upward from the fire below, as the filling of each tile is a non-conductor of heat, 60 and the conductivity of each tile itself is preferably as low as possible. Each tile has an open top through which the filling is inserted, and each tile is arranged in position with its open top facing upward so that the 65 fillings are not spilled out. The heat insula-

tion 9 can be spread over the top of each tile, thereby to further reduce the upward escape of heat from the fire below.

As shown and described, each tile, as shown in Fig. 2 or as shown in Fig. 4, has 70 provisions adapting it especially and only for overhead position in the fire arch without obstructing the insertion of the filling in each tile. In Fig. 2 the said provisions adapting each tile, as stated, comprise the 75 upper ends of the side walls 1 having the holes 3 therein, while in Fig. 4 said provisions comprise the inclined sides of each tile, which inclined sides constitute the supporting provisions whereby the tile is especially 80 adapted for overhead position in the fire arch. Also, as shown, each tile has the partitions 5 by which its side walls are braced, and whereby a cellular interior is 85 provided to receive the filling, whereby to reduce the escape of heat upwardly through the arch from the fire.

What I claim as my invention is—

1. A fire arch constructed from hollow tiles of strong refractory material, presenting a smooth surface to the fire, each tile having a filling of heat insulating material, whereby said hollow tile arch serves by said filling of each tile to reduce the escape of heat upward through said arch from the fire 90 below, and each tile having provisions adapting it especially and only for overhead position in said arch, without obstructing the insertion of said filling in each tile.

2. A structure as specified in claim 1, the filling of each tile being composed of a material which prevents transmission of the heat and which prevents any substantial or material addition to the structural strength 100 of each tile.

3. A structure as specified in claim 1, said filling within the tile comprising fine ground fire clay.

4. A structure as specified in claim 1, each tile comprising side walls and a bottom wall, 110 and partitions therein to form cells or compartments which are closed at their lower ends and open at their tops, with said filling in each compartment or cell, and heat insulating means extending over the top of 115 each tile.

5. A structure as specified in claim 1, in combination with hanger rods to support the tiles, and means to removably support the tiles on the lower ends of said rods.

6. A structure as specified in claim 1, said tiles being arranged in lateral contact with each other and being provided with overhead supporting means whereby each tile is removable for purposes of repair.

7. A tile for heat insulating purposes, comprising side walls of strong material to provide sufficient structural strength, forming an open top receptacle, integral partitions bracing the outer walls and forming cells, a 130

filling for the cellular interior of the tile formed by the receptacle, said filling being of heat insulating material, and means to support the tile with its open top facing upward.

8. A structure as specified in claim 7, and a heat insulating covering for the top, said filling being of such character that it contributes practically nothing to the structural strength of the tile.

9. A structure as specified in claim 7, said walls being of hard and refractory material to resist high temperatures and to provide

practically all of the structural strength required by the tile in use, and said filling 15 furnishing the heat insulation and contributing practically nothing to the structural strength of the tile.

10. A structure as specified in claim 7, said walls being comparatively thin and having a 20 vitreous surface, and said filling being of comparatively light insulating material of such nature that it contributes practically nothing to the structural strength of the tile.

CHAUNCEY L. C. MAGEE.
